US00D701515S

(12) **United States Design Patent**
Matas et al.(10) **Patent No.:** US D701,515 S
(45) **Date of Patent:** ** Mar. 25, 2014

- (54) **DISPLAY SCREEN OR PORTION THEREOF WITH A GRAPHICAL USER INTERFACE**
- (75) Inventors: **Michael J. Matas**, San Francisco, CA (US); **Patrick B. Corcoran**, Oakland, CA (US); **David Sloo**, Menlo Park, CA (US)
- (73) Assignee: **Nest Labs, Inc.**, Palo Alto, CA (US)
- (**) Term: **14 Years**
- (21) Appl. No.: **29/404,097**
- (22) Filed: **Oct. 14, 2011**
- (51) **LOC (10) Cl.** 14-04
- (52) **U.S. Cl.**
USPC D14/486
- (58) **Field of Classification Search**
USPC D14/485-495; 715/700-867
See application file for complete search history.

Primary Examiner — Barbara Fox*(74) Attorney, Agent, or Firm* — Kilpatrick Townsend & Stockton LLP(57) **CLAIM**

The ornamental design of a display screen or portion thereof with a graphical user interface, as shown and described.

DESCRIPTION

The FIGURE is a front view of a display screen or portion thereof with a graphical user interface showing our new design.

The broken line showing of the display screen is for environmental purposes only and forms no part of the claimed design.
